(Cl. D92—1)

Fig. 1 is a plan view of a breathable polymer coated fabric showing my new design; and

Fig. 2 is a sectional view of the fabric of Fig. 1, taken along the line 2—2.

The design is embodied in a fabric having a surface of isolated raised portions of plastic of the shapes shown in Figs. 1 and 2 of the drawing superposed on and adhering to a base made of standard strands or threads and represented by the straight line in Fig. 2 with the bodies arranged in the pattern shown in Figs. 1 and 2 of the drawing.

A complete design unit is included within the broken-

line rectangle, and this unit is reproduced in regular succession throughout the width and length of the fabric.

I claim:

The ornamental design for a breathable polymer coated fabric, as shown and described.
